UNITED STATES PATENT OFFICE.

DAVID GROVE, OF BERLIN, GERMANY.

APPARATUS FOR PURIFYING AIR.

SPECIFICATION forming part of Letters Patent No. 699,166, dated May 6, 1902.

Application filed May 29, 1899. Serial No. 718,736. (No model.)

To all whom it may concern:

Be it known that I, DAVID GROVE, engineer, a subject of the Emperor of Germany, and a resident of No. 24 Friedrichstrasse, 5 Berlin, in the Empire of Germany, have invented a certain new and useful Improved Apparatus for Purifying Air, of which the following is an exact, full, and clear description.

This invention relates to an apparatus for 10 purifying the air or removing the dust or other impurities in connection with warming, ventilating, and other industrial plants or establishments. It can also at the same time be used, if necessary, for cooling and saturating the air with water.

The apparatus consists, essentially, of cloths 15 stretched over angular frames, which former admit of freedom of movement to the air and act as a purifier by repeatedly breaking, or 20 interrupting the air-current, the impurities of the air being deposited on the cloths, which are preferably kept constantly moist or wet.

The apparatus does not act as a filter, since 25 it does not compel the air to pass through the narrow meshes of filter-cloths, which, according to experience, are soon choked up by impurities, resulting not only in annulling the effect of the filter, but also in creating doubt as to the efficiency of the whole apparatus.

30 Referring to the accompanying drawings, Figure 1 is a front elevation of the apparatus supposed to be constructed in a walled-in passage, the wet cloth, with the upper water-receptacle, being omitted. Fig. 2 is a plan

35 of same, the upper water-receptacle supposed to be removed and the cloths being shown in section. Fig. 3 is a partly longitudinal section and partly side elevation of the apparatus, some parts supposed to be broken off in or-

40 der to show others more distinctly. Fig. 4 is a cross-section through the apparatus without cloth and stretching frames. Figs. 5 and 6 are plan and side elevation, respectively, of one of the angular frames by which the 45 cloths are held tight.

The apparatus consists of a frame *a*, arranged within the channel or passage through which the air passes, so that the same is compelled to pass also through the apparatus.

50 In the frame there are secured above and

below rails or bars *b*, of angular iron, whose vertical stays are provided with indents or notches *c* for receiving the lateral lugs or projections *e* of angular frames *d*. The cloth *f* is stretched over these angular frames in 55 such a manner that it takes a zigzag course. For this purpose the one edge of the cloth is secured, as shown in Fig. 3, to the outermost lower frame *d*, conducted therefrom upwardly over the outermost upper angular 60 frame, then conducted below again and put around the next lower angular frame, and so on alternately over the upper and lower angular frames, so that the free courses or tracks of the cloth form angular spaces or 65 slots through which the air must pass. The air-current is thus repeatedly broken, and the impurities of the air remain adhering to the courses or tracks in which the cloth passes. This purifying action of the apparatus is still increased if the cloth-tracks are 70 kept always moist or wet. For this purpose a trough-shaped receptacle or vessel *g* is provided above the frame *a*, such vessel being kept filled with water up to a certain 75 level automatically by means of, for instance, the known floating-ball valve *h*. The vessel *g* is lined with cloth *i* of loose material, which is passed or fed over the edges of the trough and placed with its edges on the 80 portions of cloth *f* surrounding the angular frames *d*. The cloth *i* is preferably put around bars *j*, adapted for guiding or stretching it.

The loose cloth *i* sucks itself full with the 85 water in the trough *g* and constantly gives off water at its lower edges to the cloth *f*, so that the impurities left on the latter are washed down.

Good results are also obtained with the apparatus without wetting the cloth *f*. The water therefore can be shut off in frosty weather unless it is preferred to warm the air before it reaches the apparatus. The space above the frame *a*, carrying the cloth *f*, is 90 shut off in the direction of the air-current by a flap or folding door *k*, Fig. 4, so that the entire air must pass through the slots between the cloth-tracks. 95

Having now particularly described and as- 100

certained the nature of the said invention, I declare that what I claim, and wish to secure by Letters Patent, is—

In an air purifying and cooling apparatus,
5 one or more series of air-channels, formed of partitions or walls of air-purifying material and arranged one behind the other, diagonally to the direction of the air, in combination with a water-distributing vessel above
10 the air-channels and a cloth immersed in the

vessel, the edges of such cloth being located on the air-purifying material, as and for the purpose described.

In witness whereof I have hereunto set my hand in presence of two witnesses.

DAVID GROVE.
